UNITED STATES PATENT OFFICE.

MILTON SCHNAIER, OF NEW YORK, N. Y., ASSIGNOR TO MILTON SCHNAIER, CONTRACTING CORP., A CORPORATION OF NEW YORK.

DISTRIBUTING-VALVE.

1,187,477.

Specification of Letters Patent. Patented June 13, 1916.

Application filed July 15, 1913. Serial No. 779,092.

To all whom it may concern:

Be it known that I, MILTON SCHNAIER, a citizen of the United States, residing at the city of New York, borough of Manhattan, in the county and State of New York, have invented certain new and useful Improvements in Distributing-Valves, of which the following is a full, clear, and exact specification.

10 My invention relates to improvements in means for controlling the flow of fluid and the same has for its object to provide a simple, efficient and reliable valve by means of which the flow of fluid may be readily directed to one or the other of a plurality of outlets.

Further said invention has for its object to provide a valve having a plurality of outlets controlled by a single member which 20 serves to seal one of said outlets as it unseals the other thereof.

Further said invention has for its object to provide a secondary valve to operate in conjunction with the main valve, and which 25 secondary valve is provided with a plurality of outlets controlled by a single member which serves to seal one of said outlets and unseal the other thereof, in order to permit the flow of fluid therethrough when said 30 main valve has been opened to permit of the flow of fluid to said secondary valve.

Further said invention has for its object to provide a valve adapted for use, for example, in connection with a bath tub and a shower 35 bath and by means of which the supply of water may be admitted to said bath tub as the supply to said shower is cut off, and vice versa.

To the attainment of the aforesaid objects 40 and ends my invention consists in the novel details of construction and in the combination, connection and arrangement of parts hereinafter more fully described and then pointed out in the claims.

45 In the accompanying drawings forming part of this specification wherein like numerals of reference indicate like parts—Figure 1 is a plan view showing one form of distributing valve constructed according 50 to and embodying my said invention; Fig. 2 is a central transverse section of the same taken essentially on the line 2—2 of Fig. 1;

Fig. 3 is a central longitudinal section taken on the line 3—3 of Fig. 1 showing the valve as having unsealed the lower of the outlets 55 in said valve and adjusted to position to seal the upper of said outlets, and Fig. 4 is a similar view showing the valve as having unsealed the upper of said outlets and being adjusted to position to seal the lower of said 60 outlets.

In said drawings 10 designates a valve casing which is oblong in shape and divided horizontally by a partition 12, having a central opening 13 therein provided at its upper edge with a valve seat 14. The casing 10 is provided at one of its ends with an inlet opening within which is fitted one end of a supply pipe 15 leading from a source of water supply, and at the opposite end of said 70 casing is provided an outlet opening into which is fitted one end of a pipe 16 having its other end connected, for example, with a faucet or other suitable outlet discharging 75 into a bath tub.

From the top of the casing 10 extends upwardly a cylindrical casing portion 11 which is provided in its side directly above the opening within which the pipe 16 is secured, with an opening into which is secured one 80 end of a pipe 16^a whose other end is connected, for example, with the spray head of a shower bath. Upon the inner surface of said casing portion 11 adjacent to its lower edge are provided screw threads, and into 85 said casing portion 11 is fitted a hollow plug 17 provided upon its outer surface, adjacent to its lower edge with screw threads adapted to engage with those upon the inner surface of said casing portion 11. The plug 17 is 90 provided upon its outer surface adjacent to its upper edge with an annular bead or rim 18 which is adapted to engage the upper edge of said casing portion 11 in order to limit the inward movement of said plug 17 when 95 the same is screwed into said casing portion 11. The hollow plug 17 is provided in its outer surface intermediate the screw threads thereon, and its rim or bead 18 with a large annular groove 19, and oppositely arranged 100 openings or outlets 20, 20 which extend from said groove to the hollow central portion of said plug. In the base of said plug 17 is provided a central opening 21 which is ar-

ranged in line with the opening in the portion 12, and is provided at its lower edge with a valve seat 22.

- 23 denotes a valve stem which is centrally disposed within the plug 17, and has its lower end extending through the opening 21 in the base of said plug 17. The lower end of said valve stem 23 is screw threaded and engages with the threaded portion of a vertical opening provided in the solid upper portion or head of said plug 17. The extreme lower end of said valve stem 23 is provided with a reduced portion 24 upon which is loosely disposed a nut 25 which is maintained in position upon said reduced portion 24 by a head 26 on the lower end of said reduced portion. 27 denotes a valve member which is provided at its upper and lower edges with valve faces 28, 29 adapted to seat upon the valve seats 22 and 14, respectively, when said valve stem 23 is rotated one way or the other to raise or lower said valve member. The valve member 27 is provided in its upper surface with a central internally threaded recess 30 with which the nut 25 on the valve stem 23 is adapted to engage in order to allow said valve member 27 to revolve freely upon the lower end of said valve stem 23. The upper end of said plug 17 is reduced in diameter and internally recessed to form a stuffing box 31 to receive a packing 32 and gland 33, which are held properly in position therein by a nut 34.
- 35 The upper end of the valve stem 23 is provided with an operating handle 35, and below said handle with a downwardly extending pointer 36.
- 37 denotes a cover or face plate disposed upon the top of the plug 17, and secured in position thereon by screws 38, 38 secured to ears 39, 39 provided upon the opposite upper edges of the circular, intermediate portion 11 of the casing 10.
- 45 The operation of my valve is as follows: The water, at the desired temperature, is received through the pipe 15 and if the same is to be delivered to the bath tub faucet by way of the pipe 16, the valve member 27 should be adjusted to the position shown at Fig. 3, by turning the handle 35 to the left until the same assumes the position shown at Fig. 1 with the pointer 36 opposite the word "Bath" on the cover plate 37. When 55 the handle is so turned to the left, the valve stem 23 will be caused to rise, and the valve face 28 at the upper edge of the valve member 27 caused to seat against its seat 22 provided at the base of the plug 17. As said 60 valve face 28 is caused to seat, the valve face 29 at the lower edge of the member 27 will be caused to unseal the opening 13 in the portion 12, and thereby permit water to flow from the inlet pipe 16 into the portion of the casing above the partition 12, and

thence pass through the opening 13 in said partition into the space below said partition and pass out of said casing through the outlet opening and pipe 16 connecting with the faucet of the bath tub. When it is desired to direct the flow of water to the shower or spray head, the valve stem 23 is turned in the reverse direction and until the pointer 36 comes opposite the word "Shower". This movement of the valve 75 stem will cause the valve face 29 at the lower edge of the member 27 to close the opening 13 in the partition 12, and simultaneously therewith unseal the opening 21 in the base of the plug 17, and permit the 80 water to pass through said opening 21, and into the hollow plug 17, and thence through the openings 20, 20 and groove 19 therein to the outlet and pipe 16^a connecting said outlet with the shower spray head. 85

It will be noted that by means of my improved distributing valve I am enabled to direct the flow of water to the bath tub or the spray head by merely giving the valve stem a half turn, and that as soon as the valve member begins to open one opening it begins to seal the other thereof. Further it will be noted that as the valve is a quick-acting one, and has practically no intermediate position the valve is always in condition to permit of the passage of water therethrough to one or the other of said outlet pipes 16, 16^a. 95

Having thus described my invention what I claim and desire to secure by Letters Patent is:—

1. A valve of the character described comprising a casing having an inlet and a plurality of outlets arranged one above the other, a partition positioned between the inlet and one of the outlets and provided with an opening, said inlet and outlet being alined, a removable, hollow plug secured in the casing between the inlet and the other of said outlets, said plug having an opening 105 in its base and having an aperture in its side communicating with said other outlet, a valve positioned within the casing, and a valve stem for actuating the valve to seal either of said openings as the other thereof 110 is unsealed, substantially as specified. 115

2. A valve of the character described comprising a casing having in its lower portion an inlet and an outlet, said inlet and outlet being alined, a partition positioned between said inlet and said outlet and provided with an opening, said casing having an upwardly extending cylindrical portion provided with a second outlet, said cylindrical portion having a thread formed in its inner surface below said second outlet, a removable, hollow plug positioned within said casing and provided with a thread adjacent its base to engage the thread in said cylindrical portion, said plug having an opening in its 120 125

base and having an aperture in its side communicating with said second outlet, a valve positioned within said casing, and a valve stem for actuating the valve to seal either of said openings as the other thereof is unsealed, substantially as specified.

Signed at the city of New York, in the

county and State of New York, this 14th day of June, one thousand nine hundred and thirteen.

MILTON SCHNAIER.
